Patented Mar. 29, 1921.

UNITED STATES PATENT OFFICE.

JUNE L. CHAPLIN, OF DENVER, COLORADO.

FLEXIBLE JOINT FOR DOUBLE SWITCHES.

1,373,302.

Specification of Letters Patent. Patented Mar. 29, 1921.

Application filed July 9, 1920. Serial No. 395,092.

To all whom it may concern:

Be it known that I, JUNE L. CHAPLIN, a citizen of the United States, residing in the city and county of Denver, and State of Colorado, have invented certain new and useful Improvements in Flexible Joints for Double Switches; and I do declare the following to be a full, clear, and exact description of the invention, such as will enable others skilled in the art to which it appertains to make and use the same, reference being had to the accompanying drawings, and to the characters of reference marked thereon, which form a part of this specification.

The object of this invention is to provide a switch having two oppositely extending portions, each of which is composed of hair of full length, the two portions being united by means of a flexible neat joint which is both permanent and comfortable.

Briefly the invention comprises the uniting for each section of a plurality of strands made somewhat after the present practice, the threads projecting from the end of each section being overlapped and sewed together. One of the strands of each section is longer than the other, and this end is also wrapped into the joint and sewed. The joint is provided with a neat finish by wrapping with a wisp of hair taken from either or both of the sections.

In the drawings:

Figure 1 represents diagrammatically a single strand.

Fig. 2 shows the construction of each section after the strands thereof are twisted into shape, but before union of the sections.

Fig. 3 shows the joint partially made.

Fig. 4 represents the next stage; and

Fig. 5 the last step.

So-called fringe 10 of hair is woven upon three threads 12, as heretofore, to produce a strand 14. Each section of the double switch comprises at least one part which consists of three of said strands 14 twisted about a heavy cord 15 after the common practice, the twisted portion producing a core 16. One of the strands 14 is made longer than the other so that after said twisting operation there is an extension 114 having fringe 110, from which the threads 12 project. The two sections at this stage are shown in Fig. 2.

The next step consists in overlapping the cords 15 and threads 12 of the two shorter strands, as indicated at 112, in Fig. 3, these

overlapping parts being sewed together as represented at 20. The extending portions 114 of the longer strands are then wrapped about the overlapped portions 112 and sewed together to produce a strong bond as represented at 22 in Fig. 4.

In carrying on the last two steps, care is taken that the sewing and wrapping is not so tight as to make the joint stiff. In other words, the joint, when properly formed, is soft and flexible, but durable and permanent. The joint is then finished by selecting a wisp 25 of long hair from either or both of the sections, and wrapping each wisp 70 around the joint shown at 22 in Fig. 4 until the threads and sewing are completely hidden with hair. The tips of the wisps 25 are then threaded into a large needle 26 and drawn into the body of the sections, which 75 gives a nice finish and permanently anchors the wisps.

The result is a permanent, flexible joint having a neat, hair-wrapped finish which is both comfortable and of excellent appearance.

The number of parts, as above described, which may be joined into each section may be increased to two or three or four, as desired, and when this is done it permits the 85 parts to be braided. In fact, one part may be taken from one side of the joint and folded back onto the other side so that the joint itself is completely covered and the appearance of a braid is given, which braid 90 will be twice as long as the normal length of the hair.

I claim:

1. A hair switch comprising two switch members having their inner ends connected to form a flexible joint, said joint being relatively short and comprising a plurality of closely arranged threads extending from the members.

2. A hair switch comprising two switch members having their inner ends arranged end to end and connected to form a joint, said joint comprising a plurality of closely arranged threads bound together.

3. A hair switch comprising two switch members having their inner ends arranged end to end, and threads projecting from the ends of the two members and overlapped and connected to form a joint.

4. A hair switch comprising two switch members having their inner ends arranged end to end and connected to form a joint,

said joint being flexible and permanent and wrapped with hair to produce a neat finish.

5. A process of forming a hair switch comprising making a plurality of strands having hair fringe mounted on threads, connecting said strands to form two switch members, having said threads extending from one end of each of said members, and binding the projecting ends of the threads 10 of each section together to produce a flexible joint between the two sections.

6. A process of forming hair switches comprising making a plurality of strands having threads carrying hair fringe, connecting said strands to form two switch members from each of which said threads extend at one end, one of said strands of one member being longer than the other and projecting also at said ends, binding the 15 threads of the shorter strands of the members together to form a joint, and wrapping said projecting end of said longer strand about said joint.

7. A process of forming hair switches comprising making a plurality of strands 25 having threads carrying hair fringe, connecting said strands to form two switch members from each of which said threads extend at one end, one of said strands of one member being longer than the other and 30 projecting also at said ends, binding the threads of the shorter strands of the members together to form a joint, wrapping said projecting end of said longer strand about said joint, taking a wisp of hair from one 35 member, wrapping it about said joint to cover the same and securing the end of said wisp.

8. In a process of forming a hair switch, the step of making a plurality of strands 40 having threads carrying hair fringe, and connecting said strands to cause the ends of said threads to project whereby they may be used as connecting or attaching means.

In testimony whereof I affix my signature. 45
JUNE L. CHAPLIN.
